UNITED STATES PATENT OFFICE.

SIDNEY A. REEVE, OF NEW HAVEN, CONNECTICUT, ASSIGNOR, BY MESNE ASSIGNMENTS, TO CHARLES W. BROWN, TRUSTEE, OF PITTSBURGH, PENNSYLVANIA.

SLIDING-VALVE EXPLOSION-MOTOR.

1,169,354.

Specification of Letters Patent. Patented Jan. 25, 1916.

Application filed June 10, 1909. Serial No. 501,263.

To all whom it may concern:

Be it known that I, SIDNEY A. REEVE, a citizen of the United States, residing at New Haven, in the county of New Haven and State of Connecticut, have invented certain new and useful Improvements in Sliding-Valve Explosion-Motors, of which the following is a specification.

This invention relates to internal-combustion motors having one or more cylindrical slide-valves alined with the cylinder bore, and its principal object is to simplify the arrangements heretofore proposed while retaining the main advantages of the type.

15 A further object is to secure a better mechanical expulsion of burnt gases, improved charge-inspiration, etc.

My invention consists in certain combinations of individually-acting valves, one or 20 more of which is a slide-valve of the kind mentioned, and it further consists in improvements in the valves and their related parts, and in devices for automatically varying the cylinder clearance, preferably by 25 means of an inwardly-opening admission slide-valve.

Of the accompanying drawings, Figure 1 represents a vertical sectional view of a four-cycle motor constructed according to my invention. Fig. 2 represents a side elevation thereof. Fig. 3 represents a horizontal section on the line 3—3 of Fig. 1. Fig. 4 is a graphic representation of the relative displacements during the four phases. Figs. 5-10 inclusive represent sectional diagrams showing the valve motions. Fig. 11 represents a diagram of the exhaust-valve motion. Fig. 12 represents a diagrammatic sectional view showing a modification. Fig. 13 represents a diagram of the inlet-valve motion of Fig. 12. Fig. 14 represents a sectional view of another modification. Fig. 15 represents a detail view of the valves and connections of this modification, taken in 40 a plane at right-angles to Fig. 18. Fig. 16 represents a diagram of the valve-motion for Figs. 14 and 15, showing the admission phase.

Referring to Figs. 1, 2, and 3, 10 is the cylinder or casing having a water-jacket 12; 13 is the piston, 14 the connecting-rod, 15 the crank, 16 the crank-shaft, and 17 the half-speed shaft mounted parallel with the

crank-shaft and operated therefrom by a train of spur gearing 18, 19, 20.

55

21 is an exhaust slide-valve in the form of a sleeve concentric with the piston and constituting the barrel in which said piston slides, this sleeve being reciprocated between the piston and cylinder by means of a driving connection from the inner or crank end of the sleeve to the half-speed shaft, said connection consisting preferably of a short pitman 22 connected by one end with a crank-pin 24 on the half-speed shaft and by the other end with a lever 23 hung on fulcrum-links 32 and pivoted by trunnions to the valve 21. This valve acts individually and not jointly with another valve in controlling the motor exhaust. It might be mounted 70 and driven in various ways although I prefer that herein shown, and I also prefer a sleeve valve having an open end in the combustion chamber, as shown; that is, a free annular edge exposed to the cylinder 75 pressure so that the valve is slightly unbalanced. This shortens the motor and saves a packed or telescoped guide for the valve on the opposite end of the combustion-chamber from the end where the present 80 valve enters.

25 is an exhaust-port extending entirely around the cylinder and uncovered by the sleeve-valve 21 at the lower end of the latter's travel as indicated by the shaded area 85 in Fig. 11, wherein the numerals 1, 2, 3, and 4 indicates the positions of the half-speed crank-pin 24 at the beginning of the admission, compression, expansion, and exhaust strokes of the piston, respectively. 90 The exhaust-valve is open during slightly more than the lower quadrant of the half-speed shaft, or the distance between the lines BB and CC, the distance between AA and BB representing the entire travel of 95 the valve.

33 is a piston inlet-valve mounted in line with the cylinder bore and also acting individually to control a cylinder-admission port 38 which circumscribes the cylinder axis 100 and is interrupted by suitable guides to retain the valve packing-rings. This valve has both lower and upper rings 34, 35 and an intermediate groove 36 communicating with ports 37 formed in the cylinder wall 105 above the combustion-chamber, for leading

the charge to the valve. This valve constitutes a special form of free piston operated by fluid- and inertia-forces and controlled by a system of linkage. This valve and linkage is somewhat similar in appearance to that of my Patent 880,824, but in reality differs from it basically. My earlier invention, disclosed in my said patent, was an outwardly opening valve adapted for use in steam engines and compressors, wherein heavy unbalanced pressure was to be sustained by a toggle-linkage extended into dead center position at one extreme of its motion only, *i. e.*, the inner extreme. My present invention is for a valve adapted to sustain unbalanced pressure at both of its extremes of motion. Besides acting as a valve, this free piston 33 acts to reduce the cylinder-clearance during exhaust and to enlarge it during compression and expansion, thereby securing a better mechanical expulsion of burnt gases, a smaller volume of discharge relatively to the final volume of expansion, and other incidental advantages.

39 is a link attached by one end to the valve 33 and by the other end to a crank 40 mounted on a rock-shaft 41 and having a semicircular throw. This crank and link constitute a toggle which alternately folds and straightens at the extremes of the valve movement in obedience to fluid and inertia forces, and brings it quietly to rest without shock. With the toggle is combined a spring 45 which acts with infinite mechanical advantage on the valve at both ends of the latter's stroke and normally tends to hold the valve in an intermediate position. This spring surrounds a stud 46 and is connected with an arm 42 on the crank-shaft 40 by a tension link 43 and an arm 44 attached to the tension link and to the spring and loose on the stud 46. The tension of spring 45 is exerted in a counter-clockwise direction as viewed in Fig. 2.

47 is a spark plug which enters the cylinder opposite the untraveled space between piston 13, valve 21 and valve 33.

The motions of both valves will be readily understood from Figs. 5-10. Fig. 5 represents the end of exhaust and beginning of admission, valve 21 being on its up-stroke and valve 33 on its down-stroke. In Fig. 6 the admission-port is shown wide open with the admission-valve at the lower extreme of its movement and the exhaust valve still moving upwardly. In Fig. 7 the admission valve has started to move upwardly to close its port and the exhaust-valve is practically at the top of its stroke. Explosion occurs with the parts positioned as shown in Fig. 8, the exhaust-valve being then a short way on its down-stroke and the admission valve at the top of its up-stroke. In Fig. 9 the exhaust-port begins to open, and in Fig. 10 it is fully open and

the admission-valve starts to descend. It will be understood that (disregarding the angular inertia of the parts) the toggle 39, 40 will be unable to quite straighten in either direction owing to the infinite mechanical advantage which the toggle possesses over the valve at the ends of the latter's stroke.

By reason of the stroke and dimensions of the admission valve, the latter, in opening its port, is caused to mechanically displace practically all of the remnant of burnt gases which ordinarily cannot be reached. The resulting advantages are well known.

In Fig. 4 I have represented graphically the net volumetric displacements of the working piston and the two valves during the four phases of the motor, taking for an example substantially the relative dimensions and strokes of these parts as shown in the drawings. Reckoning the displacement during the suction stroke as 100%, the displacement during compression will then be 64%, during expansion 113%, and during exhaust 149%, indicating an expansion to a greater volume than the volume of the charge at the beginning of compression, and a practically complete expulsion of dead gases.

Fig. 12 represents a double modification consisting first in the upward extension of the exhaust-valve 21^a to guide the inlet-valve 33^a and coöperate with it in controlling admission; and secondly, in substantially reproducing by means of a positive valve-drive the motions of the free piston 100 valve of Figs. 1-10. The sleeve valve 21^a is formed with ports 38^a whose lower lips act the same as the upper lip of the valve 21 previously described, and whose upper lips act in conjunction with the admission valve 33^a to close the cylinder admission through these ports. The admission-valve is shown without its upper rings and connected with a crank 53 on the half-speed shaft through the link 39; a rock arm 49 within the admission chamber 50 inclosed by the cylinder cover, an outer rock arm 51, and a link 52. Fig. 13 represents substantially the action of valve 33^a. Its opening takes place during slightly more than one of the "end" quadrants of the crank 53. During compression the valve is moving outwardly to form a compression space and reaches its upper limit at or just before the time the exhaust valve opens, assuming considerable advance opening for the latter. During the exhaust-stroke, valve 33^a displaces the clearance gases to the extent of about 88% of the displacement attained by the free piston arrangement. Obviously the admission-valve of Fig. 12 could be used with the fixed admission-ports of Figs. 1-10 and the free piston-valve of the latter views could be used with the exhaust-valve extension and movable admission-ports of Fig. 12.

A free piston-valve of the character described might be employed without substantial alteration to control the cylinder-admission or charge transfer of a two-cycle explosion-motor.

It is characteristic of the above-described forms of my invention to employ the combination of circum-axial inlet and outlet ports (i. e. ports concentric with or substantially 10 circumscribing the cylinder axis) in different zones of the cylinder, thereby securing the advantages of large and direct openings, large valves, a pocketless combustion-chamber, direct driving connections from the 15 half-speed shaft to one or both of the valves, and permissibly, independent valves. It will, however, be understood that the inlet and outlet ports may be made to extend only part way around the cylinder, if desired.

Figs. 14, 15, and 16 represent a modification having the same general characteristics as the motor of Fig. 12 but in this case both the piston valve 33^b and the sleeve valve 21^b 25 are mounted in the cylinder-head and directly driven from an overhead half-speed shaft 17^b by means of cranks 53^b and 24^b and connecting-rods 39^b and 22^b. The exhaust-port 25 is here closed by a downward 30 movement of the cut-off lip 54 on the sleeve valve and said valve is provided with extensions 55 for retaining the rings of the piston valve, the cylinder inlet-ports being formed by the cut-off lip 54 and the sides 35 of the extensions 55.

Various other changes in embodiment may be made without departing from my invention.

It will be noted that the slide-valves here- 40 in shown and described serve to entirely overcome the use of puppet valves with their many attendant drawbacks.

I claim:

1. In an explosion motor, the combination 45 of a combustion cylinder having inlet and exhaust ports circumscribing its axis, a working piston, and an individually-acting valve controlling each of said ports, at least one of which is a tubular slide-valve, recip- 50 roated in line with the cylinder bore and the other of which works within said tubular slide-valve.

2. In a four-cycle explosion motor, the combination of a cylinder having circum- 55 ferential admission and exhaust ports in different zones, a working piston, a single axially-movable half-speed sleeve valve surrounding the piston and reciprocating be- 60 tween the piston and the cylinder wall and controlling the exhaust-port, and an independent valve mounted on the cylinder and controlling the admission-port.

3. In a four-cycle explosion motor, the combination of a combustion cylinder 5 having circumferential admission and ex-

haust ports in different zones, a working piston, a half-speed sleeve valve surrounding the piston and reciprocating between the cylinder and piston and controlling the exhaust-port, said valve having an open end 70 in the combustion-chamber, and an independent half-speed valve controlling the admission-port.

4. In a four-cycle explosion motor, the combination of a cylinder having circum- 75 axial admission and exhaust ports in different zones, a working piston, and independent half-speed cylindrical slide-valves controlling the respective ports, the exhaust valve being an unbalanced sleeve recipro- 80 cated axially between the piston and cylinder.

5. In a four-cycle explosion motor, the combination of a cylinder and piston, and independent cylindrical admission and ex- 85 haust slide-valves reciprocated in line with the cylinder bore, the admission-valve being unbalanced and opening inwardly.

6. In a four-cycle explosion motor, the combination of a cylinder having circum- 90 axial admission and exhaust ports in different zones, and independent axially-recipro- cating slide-valves controlling the respective 95 ports, the exhaust valve being an unbalanced sleeve interposed between the piston and cylinder, and the admission-valve being an inwardly-opening unbalanced piston.

7. In an explosion motor, the combination with the piston, of a free piston forming one 100 wall of the combustion chamber; and means for arresting the free piston gradually, comprising linkage reaching a dead-center position at each end of the stroke of the free piston.

8. In an explosion motor, the combination 105 with the combustion-cylinder and working piston, of a fluid-operated unbalanced piston forming one wall of the combustion-chamber, a pair of links forming a toggle which is alternately folded and extended 110 by said fluid-operated piston to arrest the same in both directions without shock, and a spring combined with the toggle for normally holding the fluid-operated valve in an intermediate position.

9. In a four-cycle explosion motor, the combination with the cylinder and working piston, of an inwardly-opening fluid-operated unbalanced piston admission-valve and means for controlling the movement of said 120 valve to effect the substantial displacement of the volume of the combustion-chamber during exhaust.

10. In an explosion motor, the combination with the cylinder and working piston, of an inwardly-opening fluid-operated unbalanced piston admission-valve for said cylinder, and toggle mechanism for arresting said valve at both extremes without shock.

11. In a four-cycle explosion motor, the combination with the working cylinder and piston, of a fluid-operated unbalanced piston admission-valve for said cylinder adapted to retreat under rising compression-pressure to form a suitable combustion-space and to return against falling exhaust pressure to displace the volume of said space during exhaust, and means for gradually arresting said valve, comprising linkage reaching a dead-center position at each of its two extremes of motion.
12. In a four-cycle explosion motor, the combination with the working cylinder and piston, of an inwardly-opening fluid-operated unbalanced piston admission-valve for said cylinder, means for gradually arresting the valve comprising linkage reaching a dead-center position at each extreme of its
13. In a four-cycle explosion motor, the combination of cylinder, working piston and shaft with a half speed shaft and a sleeve-valve controlled thereby; an inwardly opening free piston-valve forming one wall of the combustion chamber; and linkage reaching a dead-center position on each of its two extremes of motion, for gradually arresting the motion of the said free piston-valve relatively to the said sleeve-valve.

In testimony whereof I have hereunto set my hand in the presence of two subscribing witnesses, this ninth day of June, 1909.

SIDNEY A. REEVE.
